CLAIM

I claim the ornamental design for a wire end cap, as shown and described.

DESCRIPTION

FIG. 1 is a perspective view of a wire end cap, showing the side and top thereof.

FIG. 2 is a second perspective view of a wire end cap, showing the side and bottom thereof.

FIG. 3 is a third perspective view of a wire end cap, showing the bottom thereof.

FIG. 4 is a top plan view thereof.

FIG. 5 is a bottom plan view thereof.

FIG. 6 is a side elevation view thereof; and,

FIG. 7 is a cross-section view taken along line 7-7 from FIG. 6.

The broken lines in the drawings illustrate section lines and form no part of the claimed design.
